UNITED STATES PATENT OFFICE

2,493,438

JAR AND TUMBLER CAP LIFTING AND
REMOVING TOOL

Emile G. Boucher, Baltimore, Md.

Application April 1, 1946, Serial No. 658,802

4 Claims. (Cl. 81—3.46)

1

This invention relates to devices for removing caps and lids of jars and other containers and more particularly to a tool which is especially adapted to remove caps of the pressed-on type from glass jars, tumblers and other types of containers.

In my prior application Serial Number 647,900, filed February 15, 1946, entitled Jar cap remover, there are disclosed several types of prying tools which are readily adaptable for the quick and efficient removal of jar caps from jars of different sizes. The present invention constitutes an improvement over the inventions of the prior application and includes a novel construction which not only retains all of the desirable features of the prior inventions, but also adds an arrangement for efficiently removing caps from jelly glasses and similar types of containers without marring and bending such caps out of shape.

The principal object of the present invention is to provide a novel unitary tool which is capable of quickly removing caps and lids from jars, bottles, tumblers and other types of glass containers of various sizes, without marring or bending cap or lid, and without chipping or cracking the container.

A further object is to provide a tool of the above character which includes a novel arm construction which is adapted to fit beneath the lower edge of the rim of the cap and which includes cam surfaces which cooperate with the shoulder or flange of the jar to secure a powerful camming action to remove the cap upon manipulation of the tool with a minimum of effort.

Another object is to provide a novel arrangement in a tool of the foregoing type which includes a tooth or hook which is adapted to fit beneath the skirt or flange of a cap of the jelly glass type, and which cooperates with the arms of the tool to quickly remove the cap with a little effort and without bending the cap.

A still further object resides in providing a universal tool of integral and unitary construction which includes a number of cooperating parts for removing caps and lids of various sizes from glass containers, the invention being particularly useful in connection with those containers wherein the caps are securely maintained in sealing position by partially evacuating the interior of the containers.

Another object is to provide a tool of the above type which is relatively simple in construction and which may be manufactured at a relatively low cost.

Other objects and novel features of the inven-

2

tion will appear more fully hereinafter from a consideration of the following detailed description when taken in connection with the accompanying drawings. It is to be expressly understood, however, that the drawings are utilized for purposes of illustration only and are not designed as a definition of the limits of the invention, reference being had for this purpose to the appended claims.

10 Referring to the drawings wherein similar reference characters refer to similar parts throughout the several views;

Fig. 1 is a plan view of a tool constructed in accordance with the principles of the present invention;

Fig. 2 is a side view of the tool of Fig. 1;

Fig. 3 is a sectional view of the tool taken substantially along line 3—3 of Fig. 1;

15 Figs. 4 and 4a are side views of the tool associated with two different types of conventional glass jars;

Fig. 5 is a partial sectional view of the arm 28 taken substantially along line 5—5 of Fig. 1.

Fig. 6 is a partial side view of one of the arms 25 of the tool, when the cap of Fig. 4a has been partially removed;

Fig. 7 is a plan view of one end of the tool shown as being associated with the cap of a jar of the jelly glass type;

20 Fig. 8 is a partial side view of one of the arms of the tool of Fig. 7;

Fig. 9 is a plan view of the other end of the tool shown associated with the cap of a jelly glass type of container;

Fig. 10 is a partial side view of one of the arms 35 of the tool of Fig. 9;

Fig. 11 is a diagrammatic view showing the relationship of the teeth on the arms of the tool for jars and caps of different sizes;

Fig. 12 is a partial side view of one of the arms 40 showing a modified type of cap remover; and

Fig. 13 is a front view of the tool of Fig. 12.

Referring more particularly to Figs. 1, 2 and 3, a cap removing tool 20 embodying the principles 45 of the present invention is illustrated therein as including a handle part 22 provided at its opposite ends with spaced-apart pairs of arms 24, 26 and 28, 30, each of said arms being preferably formed integrally with the handle part 22. As will appear more fully hereinafter, the arms 24 and 26 50 are adapted to remove caps of the pressed-on type from bottles of different sizes, such as those presently used for packaging chili sauce, fruit juices, etc. Arms 28 and 30, on the other hand are employed for removing caps from conventional types

of glass jars of different sizes used at the present time to package canned vegetables, etc.

More particularly, and referring to Figs. 2, 3 and 5, the tool 29 is preferably formed at one end with a downwardly curved portion 32 which includes the spaced-apart arms 28 and 30 which extend forwardly of the tool and which are arranged in a plane substantially parallel to but spaced below the plane of the handle part 22. The opposite end of the tool is similarly formed with a downwardly curved portion 34 which includes the spaced-apart arms 24 and 26, these latter preferably projecting slightly upwardly, as shown in Fig. 2, although they be arranged in a plane parallel to but spaced below the plane of the handle part 22, if desired.

In order to adapt the arms 28 and 30 for removing caps from different size jars, each of the arms are provided with one or more teeth, projections or prongs which are automatically and selectively operable depending upon the size of the cap to be removed. As illustrated, the arm 28, for example, may be provided with three teeth 36, 38 and 40 which cooperate respectively with the lower rims of the flanges of the large, medium and small sizes of caps. Arm 30 on the other hand, may be provided with teeth 42 and 44, the former being for use with the larger sizes of caps while the latter is employed for the intermediate and smaller sizes. In each instance, the teeth 38, 40 and 44 are formed by curved cut-away portions, as shown in Fig. 1 while the teeth 36 and 42 are formed on the remote corners of the arms. In this manner, the arms are readily adapted for the removal of different size caps without the necessity of making any adjustments whatever.

In using the tool for removing the caps, the arms are applied beneath the lower rim of the jar cap as illustrated in Figs. 4 and 4a. In these latter figures the jars shown are of conventional type. For example the jar 46 of Fig. 4 is provided with a rim 48 for receiving the cap 50, and a shoulder 52 with which the arms 28 and 30 cooperate. In Fig. 4a, the jar 54 is likewise provided with a rim 56 for receiving the cap 50, but is formed with an outwardly directed flange or bead 58 with which the arms 28 and 30 cooperate. It is desired to point out that the front edges 60 and 62 of the arms 28 and 30 are generally curved, as shown in Fig. 1 and that when such edges are projected beneath the rim of the cap they come into contact with the neck of the jar. However, the curvature of the edges and the location of the teeth on said edges are such that irrespective of the size of the cap to be removed, the teeth will not project too far beneath the flange of the cap, during removal thereof, as to engage and become locked with the lower edges of the rims 48 or 56 of the jars. Preferably, a pair of stops 64 and 66 in the form of integral lugs are respectively formed on the remote edges of the arms 28 and 30 in order to limit the movement of the arms beneath the flange of the cap when using the tool with the larger sizes of jars.

In operation, after application of the arms beneath the cap rim, as shown in Figs. 4 and 4a, it is only necessary to press the handle part 22 downwardly whereupon a powerful camming between the arms 28, 30 and the flange 58 or neck 52 will ensue. More particularly, as the handle is moved downwardly, the inner or adjacent edges 29 and 31 of the respective arms 28 and 30 will rest upon the neck 52 or the flange 58 while certain of the teeth on the arms will project

beneath the flange of the cap, depending upon the size cap to be removed. The cooperation between said adjacent edges and the jar, during the downward movement of the handle produces the camming action referred to, and the cap is removed with very little effort and without marring or bending the same. The action of the arms, in removing the cap is shown more particularly in the partial view of Fig. 6. During the above operation, it is pointed out that as the cap is removed, the operative teeth for the particular size of cap will move in toward the jar during the pivotal movement of the edges 29 and 31 on the parts 52 or 58, and this causes a firmer fulcrum to be secured between the adjacent edges of the arms 28 and 30 and the neck 52 or flange 58. Such inward movement also compensates for the natural outward movement of the teeth due to the arc of travel of the arms 28 and 30, and thus 20 a firmer contact between the operative teeth and rim of the cap is secured.

Referring to the arms 24 and 26 at the opposite end of the tool, it will be observed that the outer edges thereof are generally curved to approximate the curvature of the necks of conventional bottles for packaging fruit juices, chili sauce, etc. In order to adapt the arms for different size bottles, arm 24 is provided with a pair of teeth 68, 70 while arm 26 is formed with a pair of teeth 72 and 74. In use, the arms are projected beneath the rim of the bottle cap and teeth 70 and 74 will become operative to remove caps from small necked bottles while teeth 68 and 72 will function to remove caps from bottles of larger sizes. The camming action during operation is precisely the same as heretofore described, it being understood that conventional bottles having pressed-on caps are provided with beads or flanges similar to 58 of Fig. 4a, and that during the removal of the cap, the adjacent edges 76 and 78 of the arms fulcrum upon such bead or flange. It is desired to point out that the outer edges of the arms 24 and 26 are formed with curved cut-away portions 80 and 82' which function as stops when the teeth 68 and 72 are cooperating to remove a bottle cap. More particularly, such portions engage the lower edge of the skirt of the cap and prevent the teeth 68 and 72 from projecting too far beneath the rim of the cap during the cap removing operation.

One of the features of the present invention is to locate the teeth 36, 38, 40, 42 and 44 in such position, that when they cooperate in removing caps of different sizes, a minimum of effort will be required. Referring more particularly to Fig. 11, there is disclosed therein, the angular relationship between the cooperative teeth for different size jars. For example, for large caps, denoted by the legend "Large," with teeth 42 and 36 cooperating, it is seen that the included angle therebetween is shown at *a*. On the other hand, with teeth 44 and 38 cooperating to remove caps of intermediate size, as shown by the legend "Medium," the included angle between the teeth 45 is represented by *b*. Also, with teeth 40 and 44 cooperating with caps of small size, denoted by the legend "Small," the included angle between the teeth is shown at *c*. It will be observed that angles *a*, *b*, and *c* are substantially equal and applicant has found that for the most efficient operation, this angle should be in the range of 80° to 90° and preferably about 85°. With such an angularity, a minimum of effort is required to remove the caps.

A further important feature of the present in-

vention resides in the incorporation in the tool heretofore described, of a novel construction for quickly and efficiently removing caps from containers of the jelly glass type without marring or bending the cap. Heretofore, caps of this type have been opened with a hook-type of opener, which so mutilates the cap that replacement on the glass is impossible. This is quite undesirable since in the case of many commodities, such as jellies and jams, the entire contents are not used at once and in order to properly preserve the rest of the contents, it is necessary to transfer the same to a different type of container having a closable lid.

More particularly, and referring to Figs. 1, 2, 3, 7 and 8, the present invention includes a hook 82 of substantial breadth, which is preferably formed integrally with the tool 20 and is positioned intermediate the arms 28 and 30. As shown in Fig. 1, the outer edge 84 of the hook 82 is slightly curved in plan, from one side to the other, and as shown in Fig. 3, is projected slightly upwardly in order to more readily fit beneath the rim of a cap. This construction forms a base 83, see Figs. 2 and 3. It will also be understood that the hook 82 may be thicker where it joins the body of the tool and may be tapered toward its outer edge 84 as clearly shown in Figs. 2 and 3.

In Figs. 7 and 8, the tool 20 is illustrated as applied to a cap 88 of a jelly glass or tumbler type of container 87, which, as is well-known, is not provided with a neck or flange as in the case of the jars 46 or 54 of Figs. 4 and 4a. As will readily appear from these figures, when the tool is applied, the outer edge 84 of the hook 82 projects beneath the skirt or flange 86 of the cap 88, while the adjacent edges 29 and 31 of the arms 28 and 30 engage the upper peripheral portion or edge 89 of the cap, at spaced apart points, see particularly Fig. 7. With the parts in this position, it will be observed from Fig. 7, that the included angle *d* between the adjacent edges 29 and 31 is the same as the angles *a*, *b* and *c* of Fig. 11 and applicant has found that this angle is also such as to readily and quickly remove caps of the type of the cap 88, from different size containers with a minimum of effort.

In operation, and with the tool assembled as shown in Figs. 7 and 8, it is only necessary to raise the handle part 22 of the tool to effect removal of the cap. More particularly, as the tool is raised, the hook 82 springs the lower portion of the flange 86 outwardly, and the portion of the cap between the adjacent edges 29 and 31 of the arms is sprung upwardly. This action breaks the seal between the cap gasket and the rim of the container and consequently breaks the partial vacuum within the container. As this action takes place, the hook slides upwardly further between the flange of the cap and the wall of the jar to allow the flange to engage the base 83 and permit the edges 29 and 31 of the arms 28 and 30 respectively to slide outwardly on the edge 89 of the cap 88. Continued movement of the tool removes the cap from the container and the sprung portion above referred to, springs back into its former shape and leaves the cap in its original condition for recapping the container.

It will be noted from the above explanation of the operation of the tool, that the edges 29 and 31 of the arms bear directly upon the edge 89 of the cap at spaced apart points. This action is highly advantageous since the force reaction is taken by the reinforced beaded rim of the container immediately beneath such points. A further advan-

tage accrues from the operation of the hook 82 in springing out a portion of the flange 86 during removal of the cap. This action ensures that the edge 84 of the hook will not engage the reinforced beaded rim of the container or the surface of the container to scratch or crack the same. From the above it will readily be seen that the angularity of the arms 28 and 30 together with the shape and location of the hook 82, enables caps of different sizes to be quickly and readily removed with a minimum of effort and without damaging the cap or the rim of the container.

If desired, the tool 20 may be provided with a pair of spaced apart hooks 90 and 92 on its upper side, see Figs. 1 and 2, which may be used to remove caps from jelly, glass type containers, in lieu of the hook 82. In such event, the tool is turned over, when applied to the container cap 88 and the hooks 90 and 92 fitted beneath the lower edge of the flange 86 and with the upper portions of the arms 28 and 30, as viewed in Fig. 1, in contact with the top surface of the cap 88. Upward movement of the tool will again spring the flange 86 of the cap 88 outwardly and upwardly to break the seal and remove the cap. It will be understood that one hook may be used in the manner of the two hooks 90 and 92, in which event, the single hook is positioned between the points where hooks 90 and 92 are positioned in Fig. 1.

A further type of cap remover for containers of the jelly glass type includes the provision of a hook 94 formed integrally with the opposite end of the tool and positioned intermediate the arms 24 and 26. In using this form of the invention, the hook 94 is placed beneath the rim 86 of the cap 88, with the arms resting on the top of the cap at the peripheral portion 89 thereof, see Figs. 9 and 10. Here again, upward movement of the handle part 22 will serve to spring the flange 86 outwardly and upwardly and the top may be readily removed without permanently bending the same out of shape.

A further form of the invention is illustrated in Figs. 12 and 13. In this form, each of the arms 28 and 30 are provided with hooks 96 and 98 which are directed forwardly and adapted to cooperate with the lower rim of the flange 86 in the manner shown in Fig. 12. In this case, due to the use of a pair of hooks, the flange is gripped and sprung at two spaced apart points, and the cover is readily removed.

From the foregoing, it will be readily understood that the present invention provides a unitary prying type of tool, which is adapted to a variety of uses. For example, the tool may be used for effectively removing jar caps of different sizes from jars, bottles, and containers of the type having pressed-on caps and which jars and bottles possess a neck or flange which functions as a fulcrum support for the camming action of the arms when the tool is in use. In operations of this character, the spacing of the teeth on the various arms insures complete and efficient adaptability to caps of different sizes, and removal thereof is easily effected without damaging the cap in any manner whatsoever and without breaking or chipping the glass. This is decidedly advantageous when only a portion of the contents of the container are used and it is desired to recap the container for future use.

In addition to the foregoing, the tool is also capable of efficient operation in removing caps from containers of the jelly glass type which are not provided with a flange or neck which could

function as a fulcrum support for the camming arms of the tool. For such use, several different arrangements have been provided, all of them involving one or more hooks or projections which are adapted to fit beneath the rim of the flange of the cap. The action of the hook or hooks, in springing the flange and edge of the cap without marring the top surface of the cap is decidedly advantageous in that the cap is removed with entire absence of permanent bends or folds. Hence the container may be readily recapped for subsequent use.

It will be also understood that if desired, the arms 28 and 30 together with the hook 82 may be utilized in order to remove caps from bottles and jars of the smaller sizes. In such use, the adjacent inner corners of the arms 28 and 29 as well as the hook 82, are placed beneath the rim of the cap and on the neck or flange of the bottle, the cap being readily removed by raising or lowering the handle. For extremely small size bottle caps, one of the arms 28 or 30 and the hook 82 may cooperate for removing the cap.

While several forms of the invention have been illustrated and described herein, with considerable particularity, it will be readily understood by those skilled in the art that various changes and modifications may be made therein, without departing from the spirit of the invention. For example while the tool has been referred to as being especially adaptable for removing caps from containers of the jelly glass type, it will be understood that this latter term includes all those containers having no flange or shoulder beneath the rim of the cap. Thus containers popularly known as Mason, Ball, Kerr, Atlas and other types of preserving jars are included in this category. It is also intended to include such containers for packaging cheese, fish and other commodities where no shoulder or flange is provided. Reference will therefore be had to the appended claims for a definition of the limits of the invention.

What is claimed is:

1. A jar cap tool for lifting and removing a cap from a jar of the tumbler or jelly glass type having a beaded rim, and wherein the cap is vacuum sealed and is provided with an annular skirt surrounding the exterior wall of the jar, comprising a handle having a pair of spaced apart arms projecting outwardly from one end of the handle, said arms lying in a common plane and provided with adjacent edges to rest at spaced apart points of support upon the edge of the top of the cap when the tool is placed in cap-removing position, and a hook projecting from said one end of the handle and positioned intermediate said arms, the hook having a base portion for receiving the lower edge of the skirt of the cap and an outer portion extending between the skirt and the exterior wall of the jar when the tool is placed in said cap-removing position, said outer portion being formed to occupy a plane different

from the plane of the arms and to be closely adjacent the inner surface of the skirt, so that said outer portion will spring the skirt outwardly from the jar wall and will readily clear the beaded rim of the jar during upward movement of the tool about said points of support to lift and remove the cap from the jar.

2. A jar cap tool for lifting and removing a cap from a jar of the tumbler or jelly glass type having a beaded rim, and wherein the cap is vacuum sealed and is provided with an annular skirt surrounding the exterior wall of the jar comprising an elongated handle having one end thereof provided with a part bent downwardly with respect to the plane of the handle, said part having a pair of spaced apart projecting arms formed integrally therewith and arranged in a common plane offset from the plane of the handle, the portion of said part between said arms being curved to generally conform to the curvature of the wall of the jar, said arms being provided with adjacent edges directed generally toward the center of the cap, and said edges resting at spaced apart points of support upon the edge of the cap when the tool is placed in cap-removing position, and a hook projecting from said part and formed integrally with said part intermediate the arms, the hook having a base portion for receiving the lower edge of the skirt of the cap and an outer portion extending between the skirt and the exterior wall of the jar when the tool is placed in said cap-removing position, said outer portion of the hook being bent upwardly with respect to said part to occupy a plane different from the plane of the arms and to be closely adjacent the inner surface of the skirt, so that the outer portion of the hook will spring the skirt outwardly and will readily clear the beaded rim of the jar during upward movement of the tool about said points of support to lift and remove the cap from the jar.

3. A jar cap tool as set forth in claim 1 wherein the outer portion of the hook is tapered to provide a thin outer edge.

4. A jar cap tool as set forth in claim 2 wherein the outer portion of the hook is tapered to provide a thin outer edge.

50 EMILE G. BOUCHER.
